Charles J. Fisher,
Letters Patent.

The Schedule referred to in these Letters Patent, and making part of the same, containing a description in the words of the said Charles J. Fisher, himself, of his Improvement in the Machine for edging or grooving Steel Plate, Sheet Iron, & the like, Copper, &c.

The utility of his edging and grooving Roller is, that a man and boy can in one hour turn the edge upon as much sheet iron, tin plate, sheeting, copper, &c, as six men can by the common mode in the same time; and with more ease, and in a more complete and workmanlike manner. The edging iron or grooving Roller, is placed under a plain roller of the same size, in any kind of frame, leaving a space between the upper and lower roller of $\frac{1}{4}$ inch. It would be proper to have a cog wheel to each roller, when the one is turned, that the other may move with the same velocity. The rollers I have in use have such a wooden base, three feet long. When I edge or groove, I have a small boy to turn the plain roller.

Explanation of the size of the rollers, they may be made of any size to suit the work that is intended to be edged or grooved; the ones I have in use are as described.

A, is the four square end 2 inches thick, to which the lever B, has fulcrum is fastened to turn the roller.

B, is the yoke or 2 inches thick on which the roller is turned.

C, is the Roller 3 $\frac{1}{2}$ inches thick, twenty eight inches long - - any thickness that will not spring.

D, is the end yoke or of the roller, 3 inches long & 2 inches thick.

1st. A plate of iron as long as the roller, 2 inches broad and $\frac{1}{4}$ inch thick the outside round as the roller, the inside flat, with an offset $\frac{1}{2}$ inch wide $\frac{1}{2}$ inch deep to form a groove.

2d. A flat plate of iron riveted to the plate 1st, to form the groove upon the outside of the roller edge. If the roller C, is made of iron, then the plate 2d, can be dispensed with - - this plate

B. J.

555. 19453 X

No. 1, can be dispensed with, is only made use of when the roller is made of wood.

No. 2, Represents the groove, $\frac{1}{8}$ inch wide $\frac{1}{8}$ inch deep, in which sheet iron, tin plate, copper, &c, is put, that is to be ground.

No. 3, is the screw that fastens the plates No. 1 & No. 2, to the roller.

No. 4, is the sheet iron, tin, copper, &c, that the edge is to be turned on. It represents the manner it is put into the roller. When the roller is turned, the edge turned on the iron, tin, copper, &c, the rollers are turned back by the iron, tin, copper, &c, taken out and the opposite edge is put in and rolled out before.

No. 5, the iron rivets by which the plates No. 1 & No. 2 are riveted together before they are secured to the roller.

No. 6, is a piece of sheet iron, tin, copper &c, after it is edged.

Charles Fisher claims the exclusive right of an Edging Iron or Ground Roller - in which the tin plate, sheet iron, sheeting copper &c, is put and the edge turned, in one or two operations from one extremity of the tin, iron, copper, &c, to the other. He also claims the right of the use of the rollers for Edging.
